DESIGN FOR A COMBINED TAX RETURN FILING PORTFOLIO AND RECORD BOOK

Bernard H. Schulist, Shaker Heights, Ohio, assignor to The World Publishing Company,
Cleveland, Ohio, a corporation of Ohio

Application April 1, 1943, Serial No. 109,887

Term of patent 3½ years

To all whom it may concern:

Be it known that I, Bernard H. Schulist, a citizen of the United States and a resident of Shaker Heights, county of Cuyahoga, and State of Ohio, have invented a new, original, and ornamental Design for Combined Tax Return Filing Portfolio and Record Book, of which the following is a specification, reference being had to the accompanying drawings, forming a part thereof.

In said annexed drawing:

Fig. 1 is a top plan view of a combined tax return filing portfolio and record book showing my new design; and

Fig. 2 is a perspective view of the same, with the folios slightly leafed apart.

I claim:

The ornamental design for a combined tax return filing portfolio and record book, as shown.

BERNARD H. SCHULIST.
